SAFETY CONTROL AND IGNITION APPARATUS FOR GASEOUS FUEL BURNERS

Victor Weber, Greensburg, and William J. Russell, Jeannette, Pa., assignors to Robertshaw-Fulton Controls Company, Youngwood, Pa., a corporation of Delaware

Application January 26, 1948, Serial No. 4,318

14 Claims. (Cl. 158—130)

1

This invention relates to safety control and ignition apparatus for gaseous fuel burners and, more particularly, to electrically operated apparatus for oven burners independent of commercial current supplies.

In copending application of Charles K. Strobel et al., Serial No. 620,320 filed October 4, 1945, and assigned to applicant's assignee there is disclosed a flash-tube or single-point oven ignition system embodying a thermoelectric safety device. The system is placed in operation by manipulation of the knob of an oven gas cock which may include a thermostatic device for control of oven temperatures. In the copending application the rotary motion of the knob is made use of during the starting period to operate a pull-wire arrangement by which a thermal timing device is positioned to determine such period.

An object of the present invention is to render such apparatus more useful by eliminating objectionable torque due to the pull-wire arrangement.

Another object of the invention is to insure positive operation of the apparatus whenever a starting period is initiated.

Another object of the invention is to eliminate undesirable forces tending to disrupt normal functioning of the control.

Another object of the invention is to simplify the mechanism and incidentally to improve the operation of the flash-tube ignition portion of the apparatus.

Another object of the invention is to locate various parts of the apparatus in low ambient temperature loads to lengthen the useful life and improve the general performance.

Other objects and advantages will become apparent from the following description taken in connection with the accompanying drawing, wherein:

Fig. 1 is a generally schematic plan view, shown partly in section, of a safety control and ignition apparatus for an oven burner embodying the invention; and

Fig. 2 is a front elevation of a portion of the apparatus shown in Fig. 1.

Referring more particularly to the drawing, the safety control and ignition apparatus is shown in conjunction with a cooking range having the usual oven burner 10 and top pilot burner 12 located remotely from the oven burner 10. As is customary in appliances of this nature, the various burners receive fuel from a manifold 14 connected to a source of fuel supply. In this embodiment, the top pilot burner 12 is connected

2

by a pipe 16 to the manifold 14 and is of the constant burning type. An ignition pilot burner 17 is preferably included and is positioned in lighting proximity to the main burner 10.

The main oven burner 10 is connected to the manifold 14 by a main fuel pipe 18 in which a main shut-off valve 20 and an electromagnetic safety shut-off means 22 are interposed as will be apparent hereinafter. The main shut-off valve 20 may embody the usual thermostatic control device which is adjustable in common therewith by an operating means in the form of a knob 24 and being responsive to temperatures in the oven where the burner 10 is located. As combined shut-off valves and thermostatic devices are well known, further description is deemed unnecessary; it being understood that the thermostatic device is capable of controlling the flow of fuel in the pipe 18 independently of the main shut-off valve 20 when the latter has once been opened. The flow of fuel in the pipe 18 to the main burner 10 is thus subject to the throttling action of the thermostatic device where included. A pipe 25 which is connected to the main shut-off valve 20 for supplying the ignition pilot burner 17 is not under thermostatic control and the flow of fuel thereto is thus unthrottled and by-passed. The electromagnetic safety shut-off means 22 is interposed in the main fuel pipe 18 in proximity of the top pilot burner 12 and comprises the casing 26 having an inlet opening 28 for the pipe 18 from the main shut-off valve 20. The inlet opening 28 communicates with a main fuel chamber 30 having a partition 32 provided with an opening 34 through which fuel may flow from the inlet 28 to an outlet opening 36 for the fuel pipe 18 to the main burner 10.

The passage 34 is controlled by a safety valve member 38 which is movable into and out of engagement with one side of the partition 32 adjacent the inlet opening 28. The valve member 38 is biased by a coil spring 40 into engagement with its seat on partition 32. A closure disc 42 is movable into engagement with the opposite side of the partition 32 and in such position serves to prevent flow of fuel through the opening 34. The closure disc 42 is slidably mounted on a reset stem 44 which extends through the opening 34 into engagement with the valve member 38 and serves to move the latter against the bias of the coil spring 40. Thus, although the valve member 38 is unseated by such operation, the closure disc 42 is simultaneously operated to prevent flow of fuel to the main burner 10. Such

interruption of fuel flow occurs during the resetting operation to be described hereinafter.

The side of the valve member 38 opposite to that engaged by the reset stem 44 is provided with a connecting stem 46 which carries at its opposite end an armature 48. The armature 48 is housed within a magnet housing 50 carried by the casing 26 and also enclosing a horseshoe magnet 52 having the usual winding 54 associated therewith. One end of the winding 54 is grounded on the magnet housing 50 and the opposite end is secured to a terminal connection 56 carried thereby.

The reset stem 44 projects through a closure cap 60 carried by the casing 26. A diaphragm element 62 extending across the inner face of the closure cap 60 and positioned between a pair of collars 58 on the reset stem 44 serves to seal against leakage from the chamber 30. A coil spring 64 extending between the closure disc 42 and the adjacent collar 58 serves to bias the closure disc 42 toward abutments 66 formed on the stem 44. A second coil spring 68 engages at one end with the closure cap 60 and at the opposite end with an abutment 70 carried on the terminal end of the reset stem 44. This spring 68 tends to bias the reset stem 44 outwardly of the casing 26 and is limited by engagement of the adjacent collar 58 with the closure cap 60.

The safety control means 22 also includes means to control the flow of fuel to an auxiliary pilot burner 72 and a thermocouple heating burner 74. The thermocouple heating burner 74 is connected by a fuel pipe 76 to the control body 26 while the auxiliary pilot burner 72 is connected by a branch pipe 77 from the pipe 76. The auxiliary pilot burner 72 is conveniently located at the rear of the top surface of the range and adjacent the control means 22 while the thermocouple heating burner 74 is located adjacent the main burner 10. Fuel from the main fuel chamber 30 is supplied to the pipe 76 by way of a passage 75 communicating at one end with the chamber 30 and at the opposite end with a pilot valve chamber 78. The pilot valve chamber 78 is provided with a seat for a pilot valve member 80 in the form of a ball member biased toward the seat by a coil spring 82. When the pilot valve member 80 is disengaged from its seat fuel may flow from the passage 75 to an outlet chamber 84 to which the pipe 76 is connected.

The pilot valve assembly is located in the body 26 laterally of the safety valve member 38 and its associated parts. Thus, an operating stem 86 for the pilot valve member 80 extends therefrom through the outlet chamber 84 and is substantially parallel with the reset stem 44. The stem 86 is reciprocable in a closure cap 88 provided with a sealing diaphragm 90 to prevent leakage of fuel at this point.

Resetting means for operating the reset stem 44 and moving the armature 48 into engagement with the magnet 52 and while simultaneously opening the safety valve member 38 takes the form of a lever device designated generally by the reference numeral 92. A lever 94 is pivotally mounted on a bracket 96 carried on a stationary portion of the range on which the apparatus is mounted. The lever 94 extends into engagement with the terminal ends of both the stems 44 and 86 and is adapted to be rotated on its pivot by a latching element 98 which is also pivotally mounted on the bracket 96 in common with the lever 94. The lever 94 and the latching element 98 are secured together by an elongated pin 100

which extends through both members and is provided with a pair of spaced cross-pins 102 one of which normally abuts the latching element 98 and the other of which is spaced from the lever 94. A coil spring 104 extends between the lever 94 and the cross-pin 102 which is spaced therefrom to provide a resilient connection of the lever 94 with the latching element 98. The arrangement is an override connection such that when the armature 48 is seated against the pole faces of the magnet 52, then any additional movement of the latching member 98 will be absorbed by compression of the coil spring 104 as the pin 100 moves relatively to the lever 94.

Movement of the latching element 98 on its pivotal mounting is effected by operating means responsive to rotation of the knob 24 of the main shut-off valve 20. To this end, a cam plate 106 is carried by the main shut-off valve 20 and is rotatable jointly with the knob 24 thereof. The cam plate 106 is adapted during its rotation to engage an arm 108 secured to one end of a connecting rod 110 and to move the arm 108 through an arc of rotation. The connecting rod 110 is rotatably mounted in the bracket 96 at one end and in a support 112 at the opposite end which projects from the main shut-off valve 20. A torsion spring 114 is mounted on the connecting rod 110 and has one end secured in the support 112 and its opposite end secured in the arm 108 for the purpose of returning the connecting rod 110 to its initial position as soon as the cam plate 106 has moved beyond the path of the arm 108. The arrangement is such that upon clockwise rotation of the knob 24 to open the main shut-off valve 20 and set the temperature at which the thermostatic control will operate, the cam plate 106 will also be moved in a clockwise direction and engage the arm 108 to rotate the connecting rod 110 in a counterclockwise direction against the bias of the torsion spring 114. After the arm 108 has been thus moved through an arc of rotation the cam plate 106 passes beyond the arm 108 and frees it for return movement under bias of the torsion spring 114.

The rotation of the connecting rod 110 is converted into a longitudinal movement for the purpose of operating the lever device 92 in the resetting operation of the safety control device 22. Such conversion of movement is effected by a nut 116 carried by the connecting rod 110 and supported by the bracket 96. The nut 116 has a stud 118 mounted therein for reciprocable movement but being held against rotation therewith by a laterally projecting arm 120 which engages with a slotted projection 122 carried by the bracket 96 for this purpose. The end face of the stud 118 operatively engages a lug 124 projecting from the latching element 98 and by means of which the lever device 92 can be moved in a clockwise direction about its pivot on the bracket 96.

The latching element 98 is retained in a latched position by the provision of a thermal timing device comprising a pivoted bimetal element 126 which is biased to latching position by a coil spring 128. The coil spring 128 engages at one end with the control body 26 and at the opposite end with one leg of a bell-crank 130 upon the opposite leg of which the bimetal element 126 is secured at one end. The bimetal element 126 is exposed to a flame from the auxiliary pilot burner 72 and is adapted to warp when heated thereby out of latching engagement with the latching element 98. The amount of warping required

to so release the latching element 98 can be increased or decreased by the provision of an adjusting screw 132 carried on a bracket 134 on the control body 26 and engaging the leg of the bell-crank 130 on the side opposite that engaged by the coil spring 128.

When the bimetal element 126 warps sufficiently and suddenly releases the latching element 98, the entire lever assembly 92 rotates counterclockwise about its pivot due chiefly to the bias of the reset stem spring 68 acting on the lever 94. Ordinarily, this rotation would be in the nature of a snap-action with the pilot valve stem 86 and the reset stem 44 moving to the left as viewed in the drawing until arrested by the respective diaphragms 90 and 62 engaging their seats. Such cessation of the snap-action would jar or vibrate the safety valve body 26 and tend to cause movement thereof in the opposite direction due to its own inertia. A separation of the armature 48 from the pole faces of the magnet 52 could therefore occur. This is obviously undesirable as the safety valve member 38 would tend to snap to closed position under bias of the coil spring 40 and shut off the flow of fuel in the main fuel pipe 18 to the main burner 10. Accordingly, this invention provides means for slowing down the counterclockwise movement of the lever device 92 to prevent the described undesirable closing of the safety valve 38 which might otherwise occur.

To this end, a gear sector 136 is carried by the lever 94 on the side opposite the side engaged by the latching element 98. This gear sector 136 meshes with a pinion 138 forming part of a gear train of which a gear 140 and a second pinion 142 form the other parts. Rotatable with the second pinion 142 is a balance-weight or fly-wheel 144 so that the entire assembly operation as will be apparent for retarding movement of the lever device 92 upon return movement of the latching element 98 and serves to prevent shock sufficient to cause separation of the armature 48 from the pole faces of the magnet 52.

The electromagnet comprising the winding 54 and horseshoe magnet 52 is adapted to be energized by current generated from a thermocouple 146 which is connected by suitable leads to the winding 54 at the terminal connection 56. The thermocouple 146 is located so that the hot junction thereof will be heated by a flame from the thermocouple heating burner 74 which receives a supply of fuel from the pipe 76 as previously described.

A system of flash tubes is provided for igniting the various burners of the apparatus from the constant burning top pilot burner 12. Accordingly, a relatively short flash tube 148 is provided between the constant burning top pilot burner 12 and the auxiliary pilot burner 72, it being apparent that fuel from the branch pipe 77 supplying the auxiliary pilot burner 72 will enter the flash tube 148 and be ignited from the constant burning pilot burner 12. The flame so created will be conducted back through the flash tube 148 and will ignite the fuel flowing from the auxiliary pilot burner 72. An elongated flash tube 150 is provided between the auxiliary pilot burner 72 and the thermocouple heating burner 74 which is remote therefrom. This flash tube 150 serves to cause ignition of the thermocouple heating burner 74 in a manner similar to that described in connection with the flash tube 148.

The heat of the flame from the thermocouple heating burner 74 on the thermocouple 146 serves

to energize the electromagnet 52 sufficiently to hold the armature 48 in attracted position but the thermoelectric current so generated is incapable of moving the armature 48 to this attracted position. Hence, the resetting means which have been described are relied upon for this purpose.

In the operation of the apparatus, it may be assumed that the parts are in the position shown in the drawing, namely, that the resetting device is in operation and that the thermocouple is still being heated by the thermocouple heating burner 74 but has not yet generated sufficient current to retain the armature 48 against the pole faces of the magnet 52. Thus, the parts are in what may be termed the starting position. In order to reach such position the dial 24 has been rotated clockwise to effect operation of the arm 108 in a counterclockwise direction by the cam plate 106. The consequent rotation of the connecting rod 110 has caused the stud 118 to actuate the lever device 92 and cause movement of the reset stem 44 and the pilot valve stem 86 to the right as viewed in the drawing. Such movement of the reset stem 44 causes the closure disc 42 to become seated against the partition 34 whereupon the stem 44 moves the valve member 38 away from its seat and the armature 48 against the pole faces of the magnet 52. At the same time, the pilot valve member 80 is moved to an open position against the bias of the coil spring 82.

The clockwise rotation of the lever 94 during the resetting operation causes the gear sector 136 to rotate the gearing mechanism described to a set position. Fuel can now flow from the main shut-off valve 20 through the main fuel pipe 18 and passage 75 in the control body 26 to the fuel pipe 76 which supplies the auxiliary pilot burner 72 and the thermocouple heating burner 74. Fuel also flows through the pipe 25 to the ignition pilot burner 17. Under these conditions the flame at the constant burning pilot burner 12 serves to ignite the auxiliary pilot burner 72 and the thermocouple heating burner 74 through the flash tube system previously described. The ignition pilot burner 17 therefore becomes ignited also by the flame at the burner 74. It will be observed that fuel in the main fuel pipe 18 cannot flow from the main fuel chamber 30 to the main burner 10 inasmuch as the closure disc 42 is held against its seat on the partition 34 due to the reset stem 58 being held inwardly by the lever member 94.

As previously mentioned, the clockwise rotation of the cam plate 106 eventually causes it to move past the arm 108 during the operation of setting the dial 24 at a desired temperature marking. As soon as this occurs the bias of the torsion spring 114 causes the connecting rod 110, and the nut 116 and arm 108 carried thereby, to rotate clockwise to the initial position. The stud 118 consequently moves longitudinally in the nut 116 to its retracted position but the lever device 92 remains in its actuated position due to the latching action of the bimetal element 126 now to be described.

The rotation of the lever member 94 in a clockwise direction by operation of the knob 24 causes the latching lever 98 also to move in a clockwise direction away from overlying relation with the bimetal element 126. Due to the bias established by the coil spring 128 on the bell-crank 130, the bimetal arm 126 moves clockwise into latching position and maintains the lever member 94 in its resetting position. Thus, during the time that the thermocouple 146 is becoming heated by the

flame from the thermocouple heating burner 74, the bimetal element 126 is simultaneously being heated by the flame from the auxiliary pilot burner 72. As the thermocouple 146 becomes heated it provides an electric potential which causes the magnet 52 to be energized for holding the armature 48 in attracted position and the valve member 38 in its open position.

When the bimetal element 126 becomes sufficiently heated it warps in a counterclockwise direction and releases the latching element 98. The entire lever assembly 92 then rotates in a counterclockwise direction about the pivot on the bracket 96 due chiefly to the bias of the reset stem spring 68 as previously described. Such return movement of the lever assembly 92 is retarded, however, by operation of the gear train 136, 138, 140 and 142 together with the inertia of the weight or fly-wheel 144 so that no shock sufficient to disengage the armature 48 and cause closing of the safety valve 38 can occur.

The pilot valve member 80 moves to closed position under bias of the coil spring 82 thus cutting off the supply of fuel to the auxiliary pilot burner 72 and the thermocouple heating burner 74. Simultaneously, the closure disc 42 moves to the left away from its seat on the partition 32 under bias of the coil spring 68. As the safety valve member 38 is now held in open position due to engagement of the armature 48 with the pole faces of the magnet 52, fuel is permitted to flow through the main fuel pipe 18 from the main fuel chamber 30 to the main burner 10 where it is ignited by the flame at the ignition pilot burner 17 which is now utilized for heating the thermocouple 146. It will be observed that the bimetal element 126 is permitted to cool during normal running conditions which should now ensue.

In the event that the flame at the pilot burner 17 is extinguished at the time that the bimetal element 126 releases the latching lever 98, then the armature 48 will not be held against the pole faces of the magnet 52 and the valve member 38 consequently closes under bias of the valve spring 40 to shut off the flow of fuel to the main burner 10. Also, during normal running operation any failure of a flame at the pilot burner 17 will permit the thermocouple 146 to cool causing a similar release of the armature 48 from the magnet 52 and consequent shutting off of fuel supply to the main burner 10.

It will be apparent that an automatic means of resetting a thermomagnetic safety device has been provided and is operable by merely manipulating the usual knob of a fuel cock from "off" to "on" position or to a desired temperature setting where a combined thermostat and main shut-off valve 20 is provided. A positive rod connection operated by rotation of the knob 24 has been substituted herein for the less desirable pull-wire operated by rotary motion as in the copending application. Moreover, the preservation of the life of the bimetal element 126 due to the limited heating time thereof remains a feature.

It will be apparent that many changes may be made in the details of construction and arrangement of parts without departing from the scope of the invention so that this description and accompanying drawing are intended by way of illustration only and are not to be construed in a limiting sense.

We claim:

1. A control apparatus for fuel burners having main and pilot burners, a main shut-off valve rotatable between positions for controlling the

fuel supply to the burners, valve means for controlling the fuel supply to the burners and being located remote from said main valve, operating means for rotating said main valve, a lever device movable into operative engagement with said valve means for conditioning the same to supply fuel to the pilot burner, connecting means for moving said lever device upon operation of said operating means, and a thermal timer biased into latching engagement with said lever device for holding the same in said operative engagement, said timer being responsive to a flame at the pilot burner for terminating said latching engagement after a predetermined period following operation of said operating means.

2. A control apparatus for fuel burners having main and pilot burners, a main shut-off valve rotatable between positions for controlling the fuel supply to the burners, valve means for controlling the fuel supply to the burners and being located remote from said main valve, operating means for rotating said main valve, a lever device movable into operative engagement with said valve means for conditioning the same to supply fuel to the pilot burner, a latching element carried by said lever device, connecting means engageable with said latching element for moving said lever device into said operative engagement upon rotation of said operating means, and a thermal timer biased into latching engagement with said latching element for holding said lever device in said operative engagement, said timer being responsive to a flame at the pilot burner for terminating said latching engagement after a predetermined period following operation of said operating means.

3. A control apparatus for fuel burners having a main and a pair of pilot burners, a main shut-off valve rotatable between positions for controlling the fuel supply to the burners, operating means for rotating said main valve, safety valve means movable between open and closed positions for controlling the supply of fuel to the main burner and being biased to said closed position, electromagnetic means operatively associated with said safety valve means for holding the same in open position when said electromagnetic means is energized, thermoelectric means responsive to the heat of a flame at one of said pilot burners for energizing said electromagnetic means, and resetting means operative for positioning said safety valve means in said open position, said resetting means including a lever device movable to a resetting position in operative engagement with said safety valve means, a latching element carried by said lever device, connecting means engageable with said latching element for moving said lever device to said resetting position upon rotation of said operating means, and a thermal timer biased into latching engagement with said latching element for holding said lever device in resetting position, said timer being responsive to the heat of a flame at the other said pilot burner for terminating said latching engagement after a predetermined period following operation of said operating means.

4. A control apparatus for fuel burners having a main and a pair of pilot burners, a main shut-off valve rotatable between positions for controlling the fuel supply to the burners, operating means for rotating said main valve, safety valve means movable between open and closed positions for controlling the supply of fuel to the main burner and being biased to said closed position, electromagnetic means operatively associated with said

safety valve means for holding the same in open position when said electromagnetic means is energized, thermoelectric means responsive to the heat of a flame at one of said pilot burners for energizing said electromagnetic means, and resetting means operative for positioning said safety valve means in said open position, said resetting means including a lever device movable to a resetting position in operative engagement with said safety valve means, a latching element carried by said lever device, connecting means engageable with said latching element for moving said lever device to said resetting position upon rotation of said operating means, and a pivoted bimetal element biased into latching engagement with said latching element and operative for maintaining said lever device in said resetting position, said bimetal element being responsive to the heat of a flame at the other said pilot burner for releasing said latching element for movement out of resetting position while said electromagnetic means holds said safety valve means in open position.

5. A control apparatus for fuel burners having main and pilot burners, electromagnetic safety valve means operable between open and closed positions for controlling the flow of fuel to the main burner and being biased to closed position, a lever device movable into operative engagement with said safety means for overcoming said bias, a thermal timer biased into latching engagement with said lever device for holding the same in said operative engagement, said timer being responsive to a flame at the pilot burner for terminating said latching engagement after a predetermined period after initial movement thereof, and means operatively associated with said lever device for retarding the rate of return movement of said lever device when said operative engagement is terminated.

6. A control apparatus for fuel burners having main and pilot burners, electromagnetic valve means operable between open and closed positions for controlling the flow of fuel to the main burner and being biased to closed position, a lever device movable into operative engagement with said electromagnetic valve means for overcoming said bias, a thermal timer biased toward latching engagement with said lever device and being responsive to the heat of a flame at the pilot burner for terminating said latching engagement, means for moving said lever device and establishing said latching engagement, and means operatively associated with said lever device for retarding return movement of said lever device when said latching engagement is terminated.

7. A control apparatus for fuel burners having main and pilot burners, safety valve means movable between open and closed positions for controlling the supply of fuel to the main burner and being biased to closed position, electromagnetic means including a movable armature connected to said valve means for holding the same in open position when said electromagnetic means is energized, a lever device movable into operative engagement with said safety valve means for overcoming said bias, a thermal timer biased toward latching engagement with said lever device and being responsive to the heat of a flame at the pilot burner for terminating said latching engagement while said armature holds said safety valve means in said open position, means for moving said lever device and establishing said latching engagement, and gearing mechanism rotatable upon movement of said lever device for re-

tarding return movement of said lever device when said latching engagement is terminated and preventing shock sufficient to cause separation of said armature from said electromagnetic means.

8. A control apparatus for fuel burners having main and a pair of pilot burners, a main shut-off valve rotatable between positions for controlling the fuel supply to the burners, operating means for rotating said main valve, safety valve means movable between open and closed positions for controlling the supply of fuel to the main burner and being biased to said closed position, electromagnetic means having a movable armature connected to said safety valve means for holding the same in open position when said electromagnetic means is energized, thermoelectric means responsive to the heat of a flame at one of said pilot burners for energizing said electromagnetic means, resetting means operative for positioning said safety valve means in said open position, said resetting means including a lever device movable to a resetting position in operative engagement with said safety valve means, a latching element carried by said lever device, connecting means engageable with said latching element for moving said lever device to said resetting position upon rotation of said operating means, a pivoted bimetal element biased into latching engagement with said latching element and operative for maintaining said lever device in said resetting position, said bimetal element being responsive to the heat of a flame at the other said pilot burner for releasing said latching element for return movement out of resetting position while said electromagnetic means holds said safety valve means in open position, and weighted gearing mechanism rotatable upon movement of said lever device for retarding movement of said lever device upon return movement of said latching element and preventing shock sufficient to cause separation of said armature from said electromagnetic means.

9. A control apparatus as claimed in claim 3 wherein pilot valve means are provided for controlling the supply of fuel to at least one of said pilot burners, said pilot valve means being movable between open and closed positions and cooperable with said lever device to be moved to said open position when said lever device is moved to said resetting position.

10. A control apparatus as claimed in claim 4 wherein pilot valve means are provided for controlling the supply of fuel to at least one of said pilot burners, said pilot valve means being movable between open and closed positions and cooperable with said lever device to be moved to said open position when said lever device is moved to said resetting position.

11. A control apparatus as claimed in claim 5 wherein pilot valve means are provided for controlling the supply of fuel to said pilot burner, said pilot valve means being movable between open and closed positions and cooperable with said lever device to be moved to said open position when said lever device is moved into said operative engagement.

12. A control apparatus as claimed in claim 6 wherein pilot valve means are provided for controlling the supply of fuel to said pilot burner, said pilot valve means being movable between open and closed positions and cooperable with said lever device to be moved to said open position when said lever device is moved into said operative engagement.

11

13. A control apparatus as claimed in claim 7 wherein pilot valve means are provided for controlling the supply of fuel to said pilot burner, said pilot valve means being movable between open and closed positions and cooperable with said lever device to be moved to said open position when said lever device is moved into said operative engagement.

14. A control apparatus as claimed in claim 8 wherein pilot valve means are provided for controlling the supply of fuel to at least one of said pilot burners, said pilot valve means being biased to a closed position and operatively engageable with said lever device when said lever device is 15

10

12

moved to said resetting position to be moved against its bias to an open position.
